UNITED STATES PATENT OFFICE

WILLIAM S. BROWN, OF CARTHAGE, MISSOURI, ASSIGNOR TO LEGGETT AND PLATT SPRING BED AND MANUFACTURING COMPANY, OF CARTHAGE, MISSOURI, A CORPORATION OF MISSOURI

BAR BENDING MACHINE

Application filed July 10, 1930. Serial No. 466,984.

My invention relates to improvements in bar bending machines.

It is particularly well adapted for forming S bends in a flat bar edgewise thereof.

One of the objects of my invention is to provide a bar bending machine of the kind described, having a cam bending member oscillative between two fulcra with means by which the cam member may be oscillated continuously or at intervals by a rotary driving shaft.

A further object of my invention is to provide novel means for varying the range of oscillation, adjustably, whereby the machine is adapted for use with bars varying in width, or the bends in the bar varied in the angles thereof.

A further object of my invention is the provision of novel means by which the bar which is being bent may be held, during the bending operation, from kinking.

Still another object of my invention is to provide a bending machine of the kind described, which is simple, cheap, strong, durable, not likely to get out of order, which enables the bar to be bent, to be easily and quickly inserted into proper position in the machine and to be easily and quickly withdrawn therefrom, after the bending operation, without stopping the machine, if desired.

The novel features of my invention are hereinafter fully described and claimed.

In the accompanying drawings, which illustrate the preferred embodiment of my invention,

Fig. 1 is a top view of the machine, with the cover removed.

Fig. 2 is a side elevation of the machine, looking at one side thereof, and showing the bar to be bent inserted ready to be bent.

Fig. 3 is a reduced elevation, partly broken away, looking at the side of the machine opposite to that shown in Fig. 2.

Fig. 4 is an enlarged section on the line 4-4 of Fig. 2.

Fig. 5 is an enlarged section on the line 5-5 of Fig. 2.

Fig. 6 is an enlarged section on the line 6-6 of Fig. 2.

Fig. 7 is an enlarged section on the line 7-7 of Fig. 3.

Fig. 8 is an elevation of the cam member, the fulcra and parts connected therewith, and showing the cam member after it has reached the limit of its bending movement, with a bar formed and held between the cams and the fulcra.

Fig. 9 is an enlarged outside elevation of the cam member crank plate.

Fig. 10 is a section on the line 10-10 of Fig. 9.

Fig. 11 is a reduced plan view of a bar which has had its end portions formed into S bends.

Similar reference characters designate similar parts in the different views.

My machine provides a suitable support for the parts comprising, as shown, a box 1 having a removable cover 2, and an L shaped bracket 3 fastened to one end of the box 1.

4 designates a flat bar which is to be bent into S bends 5, shown in Figs. 8 and 11, the bar before bending being shown in Figs. 1, 2, 4, 5 and 6.

For bending the bar into S bends there are provided two fulcra which, as shown, each comprises a roller 6 having at one end an annular peripheral flange 7, the roller being revoluble on a shouldered bolt 8 mounted in a rectangular flat plate 9 mounted on one side of the bracket 3, Figs. 2, 4, 5, 6 and 8.

The bolts 8 extend respectively through plates 10 fastened to the bracket 3.

Oscillatable in a circular recess provided in the plate 9 between the fulcra rollers 6 is a circular cam member 11 provided with two cams comprising rollers 12 respectively rotatable on shouldered bolts eccentrically mounted in the outer face of the cam member 11 said bolts being indicated by 13, Figs. 2, 4 and 8.

The cam member 11 is oscillatable between an initial bar receiving position, Fig. 2 and a bar bending position, Fig. 8.

The cam rollers 12 are each provided with oppositely disposed segmental peripheral flanges 14.

When the cam member 11 is turned from the initial position, shown in Fig. 2, after the

insertion of the flat bar 4, which is to be bent, in the direction indicated by the curved arrow in Fig. 2 the roller cams 12 will engage opposite edges of the bar 4 and force the bar against the fulcra rollers 6, thus bending the bar 4 into an **S** bend 5, as shown in Fig. 8.

The flanges 14 will engage the side of the bar 4 distant from the cam member 11, thus preventing the bar from buckling or crimping during the bending operation. The flanges 7 of the fulcra rollers 6 also engage the same side of the bar, as the flanges 14, and also prevent buckling of the bar.

For oscillating the cam member 11, the following described mechanism is provided.

The cam member 11 is provided with an axial extension 15 which extends through a hole provided in the bracket 3, and to such extension is fastened, as by a pin 16, a rigid arm 17, which is mounted in a recess 18 in the outer side of a plate 19, Figs. 1, 3, 4, and 5 to 10.

The arm 17 is pivotally engaged by the plate 19, so that the latter is adapted for circumferential adjustment relative to the arm 17 and the body of the cam member 11.

To hold the plate 19 in the position to which it is adjusted, two set screws 20 are oppositely disposed in the plate 19 at opposite sides of the recess 18, and are adapted to respectively bear against the opposite sides of the arm 17.

Rotatably mounted in one side of the box 1 is a horizontal driven shaft 21, Fig. 1 which has fastened to it outside the box 1 a crank 22 which is pivoted to a link 23, the latter being pivoted to the plate 19, Figs. 1 and 3.

The plate 19 and arm 17 form a crank in connection with the set screws 20, by which the link 23 oscillated by the crank 22, in turn oscillates the cam member 11 between the initial position and the bending position of the latter.

The adjustment screws 20, and the construction of the cam member crank, as described, are for the purpose of enabling the cam member operating on widths of material slightly different, and to enable the apparatus to be adjusted so as to obtain just the angle of bends desired in the bar to be bent.

By adjustment of the set screws 20, the range of oscillation of the cam member 11 may be changed as to position, but not as to length of oscillation of consequence.

Any suitable means may be provided for rotating the driven shaft 21. In the drawings there is shown for this purpose a driving pulley 24 fastened to a shaft 25 rotatable in the box walls 1 and having secured to it a pinion 26 which meshes with a gear wheel 27 fastened on a shaft 28 rotatable in the walls of the box 1 and having fastened on it a pinion 29 which meshes with a gear

wheel 30 fastened on a horizontal shaft 31 rotatably mounted in the box 1, Fig. 1.

A clutch of any suitable design and designated in Fig. 1 by 32 is adapted to drivingly engage the shaft 31 with the shaft 21 having the crank 22.

The clutch may be operated by any suitable means, as by a rock shaft 33 oscillative in the walls of the box 1 and provided with a crank 34 engaging the clutch mechanism, 75 and having also a crank 35 connected by a link 36 to a vertically depressible treadle 37 pivoted to the box 1 and normally lifted to the clutch disengaging position by a coil spring 38 fastened at its upper end to the box 1 and at its lower end to the treadle.

In the operation of the machine, the parts being as shown in Fig. 2, the operator places a bar 4 in the operative position between the fulcra rollers 6 and the cam rollers 12. He 85 then depresses the treadle 37, thus causing the rotating shaft 31 to drive the shaft 21 through the clutch mechanism 32.

The shaft 21 will revolve a complete revolution, the operator removing his foot from the treadle after having depressed it to engage the clutch with the shaft 21. The shaft crank 22 on revolving a revolution will oscillate the crank plate 19, and with it the set screws 20, arm 17 and cam member 11 in the 95 manner already described, thus causing the cam rollers 12 and fulcra rollers 6 to make an **S** bend 5 in the bar 4.

Upon the return of the cam member 11 to its initial position, the bent bar 4 may 100 be removed and another substituted for it, and the operation then repeated.

The crank 22 is shorter than the cam crank plate 19 and its pivotal connection with the link 23 is at a less distance from the axis of the 105 shaft 21, than the distance of the pivotal point of the link with the plate 19 is from the axis of the cam member 11. This construction enables the rotation of the shaft 21 to oscillate the cam member 11.

As shown in Figs. 2 and 8, a stop gage plate 39 is attached to the lower end of the plate 9 against which the lower end of the bar 4 may be projected, when the bar is inserted between the cam rollers 12 prior to 115 the bending of the bar, so that the **S** bend in the bar will be made at the proper distance from the adjacent end of the bar.

I do not limit my invention to the structure shown and described, as many modifications, within the scope of the appended claims, may be made without departing from the spirit of my invention.

What I claim is:

1. In a bar bending machine, a support 125 having two fulcra adapted to respectively engage opposite edges of a bar to be bent, a cam member oscillative on said support between said fulcra and having two cams adapted to respectively engage said edges of said bar, a 130

rotary shaft, and means connecting said shaft and said cam member by which, upon each rotation of said shaft, said cam member will be turned, first, in a direction such that said cams will force said bar against said fulcrum to form an **S** bend in the bar, and then in the opposite direction to its initial position.

2. In a bar bending machine, a support having two fulcrums adapted to respectively engage opposite edges of a bar to be bent, a cam member oscillative on said support between said fulcrums and having two cams adapted to respectively engage said edges of said bar, a rotary shaft having a crank, said cam member having a crank which is longer than the shaft crank, and a link connecting said cranks, whereby, upon each rotation of said shaft, said cam member will be turned, first, in a direction such that said cams will force said bar against said fulcrums to form an **S** bend in the bar, and then in the opposite direction to its initial position.

3. In a bar bending machine, a support having two fulcrums adapted to engage respectively opposite edges of a bar to be bent, a cam member oscillative on said support between said fulcrums and having two cams adapted to respectively engage said edges of said bar and adapted, when said cam member is turned from an initial position in one direction, to force said bar against said fulcrums to form an **S** bend in the bar, each of said cams having oppositely extending segmental peripheral flanges adapted, when said cam member is turned in said direction, to overlap and engage the side of the bar distant from said cam member, and means for turning said member to and from said initial position.

4. In a bar bending machine, a support having two fulcrums adapted to respectively engage opposite edges of a bar to be bent, a cam member oscillative on said support between said fulcrums and between an initial bar receiving position and a bar bending position and having two cams adapted to respectively engage said edges of said bar and adapted, when said cam member is turned from said initial position to said bending position, to force said bar against said fulcrums to form an **S** bend in the bar, each of said cams having a peripheral segmental flange adapted, when said cam member is turned from said initial position to said bending position, to overlap and engage the side of the bar distant from said cam member, and means for oscillating said cam member between said positions.

5. In a bar bending machine, a support having two fulcrums adapted to respectively engage opposite edges of a bar to be bent, a cam member oscillative on said support between said fulcrums and between an initial bar receiving position and a bar bending position and having two cams rotative thereon adapted to respectively engage said edges of said bar and

adapted, when said cam member is turned from said initial position to said bending position, to force said bar against said fulcrums to form an **S** bend in the bar, each of said cams having a peripheral segmental flange adapted, when said cam member is turned from said initial position to said bending position, to overlap and engage the side of the bar distant from said cam member, and means for oscillating said cam member between said positions.

6. In a bar bending machine, a support having two fulcrums adapted to respectively engage opposite edges of a bar to be bent, a cam member oscillative on said support between said fulcrums and between an initial bar receiving position and a bar bending position and having two cams adapted to respectively engage said edges of said bar and adapted, when said member is turned from said initial position to said bending position, to force said bar against said fulcrums to form an **S** bend in said bar, said cam member having a crank circumferentially adjustable relatively to the body of said cam member, and means engaging said crank for oscillating said cam member.

7. In a bar bending machine, a support having two fulcrums adapted to respectively engage opposite edges of a bar to be bent, a cam member oscillative on said support between said fulcrums and between an initial bar receiving position and a bar bending position and having two cams adapted to respectively engage said edges of said bar and adapted, when said cam member is turned from said initial position to said bending position, to force said bar against said fulcrums to form an **S** bend in said bar, said cam member having a portion rigid with the body of said cam member, the cam member having a crank pivotally engaging said rigid portion so as to have circumferential adjustment relatively thereto, said crank having adjustable means engaging said rigid portion for holding said crank in the position to which it is adjusted, and means engaging said crank for oscillating the same.

8. In a bar bending machine, a support having two fulcrums adapted to respectively engage opposite edges of a bar to be bent, a cam member oscillative between said fulcrums and between an initial bar receiving position and a bar bending position and having two cams adapted to respectively engage said edges of said bar and adapted, when said cam member is turned from said initial position to said bending position, to force said bar against said fulcrums to form an **S** bend in the bar, said cam member having a rigid radial arm and a crank comprising a radial plate pivotally engaging said arm so as to be circumferentially adjustable relatively thereto and having two oppositely engaged set screws respectively engaging opposite sides of said arm for holding said plate releasably in the

position to which it may be adjusted, and means engaging said plate for oscillating the latter and with it said cam member.

9. In a bar bending machine, a support having two fulcra adapted to respectively engage opposite edges of a bar to be bent, a cam member oscillative between said fulcra and between an initial bar receiving position and a bar bending position and having two cams adapted to respectively engage said edges of said bar and adapted, when said cam member is turned from said initial position to said bending position, to force said bar against said fulcra to form an **S** bend in said bar, said cam member having a crank circumferentially adjustable relatively to the body of said cam member, a rotary shaft having a crank, and a link pivoted to the shaft crank and pivoted to said cam member crank at a radial distance greater than the distance from the axis of said shaft to the pivotal point of the link with said shaft crank, whereby, upon each rotation of said shaft, said cam member is oscillated.
10. In a bar bending machine, a support having two fulcra adapted to respectively engage opposite edges of a bar to be bent, a cam member oscillative between said fulcra and between an initial bar receiving position and a bar bending position and having two cams adapted to respectively engage said edges of said bar and adapted, when said cam member is turned from said initial position to said bending position, to force said bar against said fulcra to form an **S** bend in said bar, said cam member having a rigid radial arm and a crank comprising a plate pivotally engaging said arm so as to be circumferentially adjustable relatively thereto and having two oppositely disposed set screws respectively engaging opposite sides of said arm for holding said plate in the position to which it may be adjusted, a rotary shaft having a crank, and a link pivoted to said plate and said shaft crank and pivoted to said plate at a distance from the axis of said cam member greater than the distance between the axis of said shaft and the pivotal point of said link with said shaft crank, whereby, on each rotation of said shaft, said cam member is oscillated.

In testimony whereof I have signed my name to this specification.

WILLIAM S. BROWN.
